FREDRIC E. DOUGLAS, OF HOPEDALE, MASSACHUSETTS, ASSIGNOR TO DRAPER CORPORATION, OF HOPEDALE, MASSACHUSETTS, A CORPORATION OF MAINE

FILLING REPLENISHING SHUTTLE

Application filed May 14, 1930. Serial No. 452,359.

This invention relates to loom shuttles and is more particularly directed to shuttles of the filling replenishing type wherein the bobbin or filling carrier in the shuttle is changed from time to time.

It is now the ordinary practice to provide filling replenishing shuttles with a shuttle spring formed with bobbin holding jaws sufficiently stiff to support the filling carrier or bobbin in the shuttle and yet possessed of sufficient resiliency to permit the automatic substitution of one filling carrier or bobbin for another from time to time. When filling replenishment is effected, the bobbin holding jaws are suddenly separated or flexed outwardly as the outgoing filling carrier or bobbin is ejected and then suddenly approach each other or are flexed inwardly as the fresh filling carrier or bobbin finds its operative position between the bobbin holding jaws.

The shuttle spring is usually secured in the shuttle by a transverse bolt which passes through a bolt hole formed in the shank portion of the shuttle spring and the sudden flexing of the jaws first in one and then in the opposite direction has caused the jaws to break, particularly at or near the bolt opening where the shank of the shuttle spring affords a zone which is less stiff or more easily responsive to the movements of the bobbin holding jaws.

One of the purposes of the present invention is to provide a shuttle spring in which the pronounced zone of weakness at the bolt opening of the shank may be avoided and the jaws of the shuttle spring be allowed to flex along an area of the shank extending a substantial distance longitudinally thereof, thus distributing the flexure movement of the jaws and preventing breakage.

It has been common heretofore to insert a metal separator or filler block in the shank of the shuttle springs to prevent the transverse bolt from drawing the walls of the shuttle inwardly, but the unyielding nature of such separators or blocks has only emphasized the liability of jaw breakage by confining the flexure of the jaws to the already weakened and limited zone passing

vertically through the bolt opening of the shank.

Another feature of the invention, therefore, consists in providing a wooden filler block which is seated in the shank portion of the shuttle spring and serves as an elastic medium to cushion the action of the bobbin holding jaws in their movements towards and from each other. It has been found that a wooden filler block impregnated with a lubricant, such as oil or the like, will offer such a cushioning effect to the movement of the bobbin holding jaws as to contribute largely to non-breakage.

The invention and novel features thereof will best be made clear from the following description and the accompanying drawings of one good form thereof.

In the drawings:

Fig. 1 is a longitudinal section of a filling replenishing shuttle provided with the present invention, part of the shuttle being broken away;

Fig. 2 is a top plan view of the shuttle spring having the wooden filler block seated in the shank portion thereof and showing also the vertical or through-bolt between the end of the wooden filler block and the bend of the shuttle spring; and

Fig. 3 is an exploded view of the parts constituting the present invention, showing them in their relative positions for assembly.

The shuttle 1 may be of the usual filling replenishing type provided with the bobbin chamber 2 and the shank receiving chamber 3 and these parts may be of usual or any preferred construction.

The shuttle spring embodies the bobbin holding jaws 4 and 5 which may have their end portions provided with a downward bevel 6 and recesses 7 for engagement with the usual rings on the bobbin head, and these parts may be as usual. The shuttle spring as shown in the present instance has a shank portion which when the parts are assembled is seated in the shank receiving chamber 3 of the shuttle. As shown, the shank consists of two leg portions 8 and 9 which are preferably joined together at the bend 10, and extending outwardly from the

two legs 8 and 9 of the shank are the bobbin holding jaws 4 and 5.

The shank portion of the shuttle spring is provided with a slot 11 which extends longitudinally of the shank and communicates with the opening through which the transverse bolt 12 passes when the parts are assembled, as indicated in Fig. 1.

Preferably a slot 11 is formed in each leg portion 8 and 9 of the shank and extends from the bolt opening to the rear end of each leg portion of the shank where the two slots merge or communicate. From this construction it will be apparent that the bobbin holding jaws may flex not only at the single opening for the bolt as heretofore was the practice, but throughout the length of the shank portion from the bolt opening to the end of the leg portions of the shank, thereby distributing the spring action of the jaws.

In order that the sudden action of the bobbin holding jaws may in a measure be cushioned, the present invention contemplates a wooden filler block 13 which may be seated between the legs 8 and 9 of the shank portion of the shuttle spring, as more clearly indicated in Figs. 1 and 2, and in order that the cushioning effect of the wooden block 13 may take up the spring action of the jaws during replenishment without detriment thereto, the forward end portion of the wooden filler block 13 is extended beyond the bends 14 of the bobbin holding jaws, with the result that the wooden filler block imparts a more extended bearing to the jaws as they flex during replenishment than would be the case should the filler block present corner portions to the action of the jaws.

In some cases it is sufficient to form the filler block of suitable wood to impart an elastic or cushioning effect to the jaws, but preferably the wooden block will be impregnated with a lubricant such as oil or the like whereby the cushioning effect of the block is increased.

The wooden filler block 13 is provided with an opening 15 through which passes the transverse bolt 12 when the parts are in assembled position as indicated in Fig. 1.

In assembling the parts the shuttle spring has the shank portion thereof seated in the shank receiving chamber of the shuttle and the wooden filler block is seated between the leg portions of the shank. It is common in filling replenishing shuttles to provide a bobbin guide for directing the bobbin into position between the bobbin holding jaws during replenishment, and such bobbin guide may be formed as indicated in Fig. 3 wherein there is a top plate 16 and a bottom plate 17 joined by the inclined guide 18 which extends between the base portion of the bobbin holding jaws. The top and bottom plates 16 and 17 are each provided with an opening 19 and when the bobbin guide is placed in position,

as indicated in Fig. 1, and the transverse bolt 12 has been passed through the slotted portion of the shank of the shuttle spring and the opening 15 of the wooden block, the bobbin guide is moved to place between the bobbin holding jaws and the through-bolt 20 is passed through the openings 19 in the top and bottom plates of the bobbin guide and between the bend 10 of the shank and the end of the wooden filler block 13, with the result that the through-bolt 20 serves effectively to prevent longitudinal movement of the shuttle spring relative to the shuttle.

The through-bolt 20 likewise passes through an opening in the wood of the shuttle below the lower plate 17 and is there engaged by a nut 21 for locking the through-bolt and the associated parts in operative position.

From the construction described it will be apparent that the slots 11 in the leg portions of the shank of the shuttle spring extend from the opening for the transverse bolt 12 longitudinally of the shank and about the bend thereof where the two slots communicate, thereby providing an extensive yielding portion in the shank and distributing the strain of the bobbin holding jaw movements substantially throughout the shank portion of the shuttle spring.

The elastic nature of the wooden filler block serves also to cushion the movement of the bobbin holding jaws so that during replenishment rupture or breakage of the bobbin holding jaws as heretofore experienced is entirely obviated and the bobbin holding jaws move with less strain or crystallizing effect upon the metal.

Obviously, changes may be made in the details of some of the parts, the main characteristic of the invention residing in distributing the strain of flexure of the bobbin holding jaws so danger of breakage is avoided, even after long usage. It will also be noted that the wooden block acts with a cushioning effect upon the bobbin holding jaws and cooperates with the distribution of jaw movements due to the longitudinal slots in the shank portion of the shuttle spring, during replenishment of filling.

What is claimed is:

1. A filling replenishing shuttle having a bobbin holding spring comprising two bobbin holding jaws, and an integral shank connecting the jaws and provided with a slot in each leg of the shank which extends to and about the bend of the shank to form a yielding zone for the jaws during replenishment, a transverse bolt passing through the slots, and a bolt passing vertically through the shank inside the bend thereof.

2. A filling replenishing shuttle having a shank receiving chamber, a shuttle spring having a shank seated in said chamber and bobbin holding jaws, each leg of the shank having a slot extending to the end of the

shank, a wooden filler block seated between the legs of the shank and presenting an elastic medium for the bobbin holding jaws during replenishment of filling.

5 3. A filling replenishing shuttle having a bobbin spring comprising a shank and bobbin holding jaws, and a wooden filler block seated in the shank of the shuttle spring and presenting an elastic cushion to the bobbin holding jaws as they are flexed during replenishment of filling.

10 4. A filling replenishing shuttle having a shank receiving chamber, a shuttle spring comprising a shank seated in said chamber and provided with bobbin holding jaws, a filler block seated in the shank of the shuttle spring and formed of wood impregnated with a lubricant to increase its elastic character that the wooden filler block may act 15 as an elastic cushion for the bobbin holding jaws as they are flexed during replenishment of filling.

20 5. As an article of manufacture, a shuttle spring having bobbin holding jaws and a shank integrally connecting the jaws and 25 provided with a bolt opening in each leg of the shank and a slot extending longitudinally of each leg of the shank from the bolt opening and about the bend of the shank.

30 6. As an article of manufacture, a shuttle spring comprising bobbin holding jaws each having a leg portion provided with a transverse bolt opening and a slot extending backwardly from each bolt opening to the terminal ends of the leg portions of the bobbin holding jaws.

35 7. As an article of manufacture, a shuttle spring formed of a single piece bent to form a shank portion and two bobbin holding 40 jaws, a bolt opening in each leg of the shank portion, and a slot extending about the bend of the shank portion and communicating with the two bolt openings to provide a zone of flexure from the bolt openings to the bend 45 of the shank.

In testimony whereof, I have signed my name to this specification.

FREDRIC E. DOUGLAS.
